UNITED STATES PATENT OFFICE.

EDWARD R. BURDEN, OF SIDNEY, OHIO.

CAR-COUPING.

SPECIFICATION forming part of Letters Patent No. 530,065, dated November 27, 1894.

Application filed August 16, 1894. Serial No. 520,471. (No model.)

To all whom it may concern:

Be it known that I, EDWARD R. BURDEN, a citizen of the United States, residing at Sidney, in the county of Shelby and State of Ohio, 5 have invented certain new and useful Improvements in Car-Couplers, of which the following is a specification, reference being had therein to the accompanying drawings.

My invention relates to an improved automatic car-coupler of the class in which the draw-bar is provided with a pivoted hook and a recess for the reception of a similar pivoted hook carried by the draw-bar of the adjoining car.

15 The object of my invention is the production of a coupler of this class having improved means for simultaneously raising both hooks out of coupling engagement with the respective draw-bars, and which can be operated 20 either from the top or side of a car; to pivot each hook in such manner that its pivot-pin will serve as the coupling-pin for the hook on the adjacent draw-bar; and to so construct and arrange the parts that cars of different 25 heights may be readily and securely coupled automatically.

The invention will first be described in connection with the accompanying drawings, and then pointed out in the claim.

30 Figure 1 of the drawings is a perspective view showing a car provided with my coupler. Fig. 2 is a broken longitudinal vertical sectional view of two draw-bars, showing the construction of my coupler and also the positions of the parts when cars of the same height are coupled. Fig. 3 is a like view showing the 35 positions of the parts when cars of different heights are coupled. Fig. 4 is a perspective illustration of the manner in which the draw-bars are coupled together. Fig. 5 is a transverse sectional detail view through one of the draw-bars, taken on the line $x-x$, Fig. 1.

40 Referring to the drawings, A and A' represent the draw-bars, in each of which are formed two recesses B and C, the former being open on top nearly its whole length, while the top opening of the latter is much shorter. At the lower forward end of each recess is a solid abutment 1, for a purpose hereinafter 45 mentioned.

D and D' are two hooks, each having a long

upwardly-inclined face 2 and a rearwardly-extending arm 3.

E and E' are what I term the "coupling-pins," one being passed through and secured 55 in the forward end of each draw-bar.

Hook D is pivoted on coupling-pin E in recess C in draw-bar A, and is adapted to pass into the recess B in the abutting draw-bar and engage with the coupling-pin E', the arm 60 3 of the hook extending rearwardly to near the end of the recess C in draw-bar A. Hook D' is pivoted on coupling-pin E' in recess C in draw-bar A', and is adapted to engage with coupling-pin E in recess B in draw-bar A, the 65 arm 3 of said hook extending rearward to near the end of recess C in draw-bar A'.

F is a dog pivoted in recess B in each draw-bar in such manner that one of its ends will normally rest on the abutment 1 and underlie 70 the nose 4 of the hook when a coupling is made.

G is the operating-rod, which passes through keepers 5 in the end of the car and extends upward a short distance above the top of the car, and is there pivotally connected with a lever 75 5, fulcrumed in a suitable bracket 6 secured to the foot-board. Another lever g' is also pivotally connected to rod G and extends in a lateral direction slightly beyond the side of the car, said lever being fulcrumed in a 80 bracket 7 secured to the end of the car. The lower end of this operating-rod is bifurcated, as seen in Figs. 1 and 5, one of its stems 8 passing through a slotted opening 10 in the draw-bar and bearing on the end of hook-arm 85 3 in recess C, the other stem 9 passing through a like opening 11 in the draw-bar and bearing on one end of the dog F in recess B. As the hook-arm 3 describes a greater arc of a circle in raising the hook from engagement with the 90 coupling-pin than does dog F, stem 8 is necessarily made longer than stem 9, as seen in Fig. 5; and therefore in order that the shorter stem may at all times be kept in proper relation to the slotted opening 11, I form a wall 95 12 around the top of said opening, leaving an open space 13 in the wall adjacent to the slotted opening 10, in order to permit that part of the rod G that connects its stem to enter in the downward movement of said rod. 100

On the under side of the front end of the draw-bar is formed a lug H, having an elong-

gated opening 15, in which is hung an ordinary link I, for use with cars not provided with my coupler.

In Figs. 2 and 4 I have shown the draw-bars 5 coupled in the same plane; but with my coupler cars that are of different heights may be readily coupled, the parts in that event assuming the relative positions shown in Fig. 3.

- The operation of my coupler is very simple 10 and requires but little description. As two cars provided with this coupler come together the hooks on the respective draw-bars come into contact with the coupling-pins, riding up over and falling into engagement with them. 15 In uncoupling, all that is necessary is that the brakeman, standing at the side of a car or on top of it, depress the operating-rod G, when its stem 8 will depress the hook-arm 3 and thus release its hook from the coupling- 20 pin, and stem 9 will cause dog F to raise the nose of the other hook clear of the coupling-pin, the dog being limited in its movement for this purpose by a pin 14 secured in the recess B.

Having thus described my invention, what 25 I claim as new, and desire to secure by Letters Patent, is—

In a car-coupler, two draw-bars, each having two parallel recesses, open above and below, and an abutment at the lower forward end of each recess, a coupling-pin passed through both recesses, a gravity dog pivoted in one of the recesses so that its forward end rests normally on the abutment, a hook pivoted on the coupling-pin in the other recess, 30 said hook having an inclined face projecting above its upper edge and a rearwardly-extending arm, and a bifurcated rod bearing loosely on the rear end of the dog and on the arm of the hook, substantially as described 35 and for the purposes stated.

In testimony whereof I affix my signature in presence of two witnesses.

EDWARD R. BURDEN.
